UNITED STATES PATENT OFFICE.

JOSEPH DAVID SCHMIDT, OF BERKELEY, CALIFORNIA.

HEATER.

Application filed February 8, 1923. Serial No. 617,871.

My invention relates to a device for heating solid, liquid, or gaseous matter, by the transmission of heat from a heated gas or liquid of any nature. It relates more particularly to a device for heating a room by the transmission to the air of the room of heat from the gases of combustion of any suitable material, more especially from the combustion of gas.

10 An object of my invention is to provide a heater having a series of thin, hollow partitions or walls placed close together, open at the bottom and top for the circulation of air, and a source of heat at one edge of 15 the assembled hollow partitions, and an exit for the products of combustion at the opposite edge. A further object is to force the flow of the products of combustion over the surfaces of the hollow partitions by placing 20 the exit for such products at a low position in the side opposite the source of heat.

In my specific construction, I have a box-like sheet metal structure supported on legs with a plurality of thin, hollow partitions 25 placed close together with their outside edges separated from the end walls of the structure. These partitions are open at the bottom, drawing air from the floor of the room and have a hood receiving the heated air 30 from the top, whence it is discharged into the room. At one end of the structure, preferably along the bottom end edges of the hollow partitions I place a gas burner having a suitable valve, and air inlet to provide 35 for the combustion. At the opposite end of the structure, and the opposite edges of the hollow partitions, the exit for the products of combustion is placed low down in order to force the flame and burnt gases to 40 take a longer path of travel over the surface of the hollow partitions. A stove pipe, or other flue, may be connected to the gas exit outlet.

I attain these objects by the device illustrated in the accompanying drawings in which Fig. 1 is a vertical section taken lengthwise, Fig. 2 is a horizontal section, and Fig. 3 is an end view of a device embodying the principles of my invention. 50 Figure 4 is an enlarged detail view.

It is understood that the drawings are intended for purpose of illustration only, and that various changes may be made in the size, shape, proportions, and minor details without departing from the spirit or sacrificing any of the advantages of the in-

vention as claimed. I also desire it to be understood, that the principles of my invention may be applied to a number of uses and that I do not wish to be limited in my 60 claims to the particular use shown, where I illustrate the principles of my invention as applied to a gas heater as used in heating the air of a room.

In the drawings similar numerals are used 65 throughout the several views for referring to similar parts.

The drawings show a rectangular metal box or casing, 1, having a long gas burner, 2, extending across the bottom of one end, 70 and a vent opening and pipe, 12, equidistant from the sides at the other end slightly higher than the level of the top of the flame of the burner.

The vent pipe, 12, is shown fastened to 75 the box, 1, by rivets, 13. The burner is shown equipped with a mixer, 3, a valve, 4, and a connection for attachment to a gas line, 5. The burner enters the rectangular box, 1, through suitable openings and is 80 held in position by suitable fastening.

Should the box, 1, have a top and a bottom with nothing inside of it, in operation the entire box, 1, would be filled with the hot gases of combustion enroute to the flue from the burner. The drawings however show the volume of this box broken up by the spacing of a plurality of rectangular air flues, 9, which connect the top and bottom of the box, 1, and are open at the top and 85 bottom so that the air which they contain is free to circulate upward into the room upon being heated.

Between each of these air flues, 9, is a 90 space, 8, through which the hot gases of combustion may pass on their way from the burner, 2, to the vent pipe, 12. The spaces, 8, are closed at the top and bottom to prevent the hot gases of combustion entering the air in the room, and the air flues, 9, are 100 closed at the ends next to the burner and flue to prevent the combustion gases entering the air flues, 9.

The top and bottom of the box, 1, are not shown affixed to the box, 1, but are shown 105 affixed to the air flues, 9, in such a manner that if desired, the top and bottom together with the air flues, 9, may be removed from the box, 1, by being lifted upward. The junction of the top and bottom of the box, 1, 110 with the sides of the box, 1, is made tight against the escape of the gases of combustion

by the top and bottom resting upon lips, 19, and, 20, respectively, said lips being a part of the sides and ends of the box, 1. The weight of the air flues tends to seal this junction sufficiently to prevent escape of gases of combustion into the room. The top and bottom may be fixed to the box, 1, with a sealed joining but I prefer them removable as shown.

10 A hood, 14, may be used to direct the current of heated air in an effective direction.

The box, 1, and air flues, 9, may be made of any suitable material, but I prefer them made of sheet iron.

15 Any suitable burner may be used, but I prefer an elongated burner for purpose of economy of space and equal distribution of the gases of combustion. Any suitable mixer, valve, and connection may be used 20 with the burner.

Any suitable means may be used for fastening together the various parts, but I prefer the junctions welded.

25 The box, 1, may be supported by metal legs, 15, bolted to the box.

It can easily be seen that in the application of the principles of the heater to a gas heater for heating a room, a device has been provided which will not discharge any harmful burnt or unburnt gas into the room, and yet will secure maximum heating from the gas consumed. It will occupy minimum space in proportion to its amount of heating surface. It may easily be disassembled for 35 cleaning or repairing. It provides means for deflecting the heated air in an effective direction, and it provides a heater for a house or room which will be healthful and economical in its use. Moreover it is of such 40 construction that it will neither be difficult nor costly to manufacture.

45 It will be apparent from the above description in connection with the drawing that the products of combustion from the burner follow along each side of each hollow partition. As these partitions are quite thin and the space between them is narrow the products of combustion are brought into contact with a large heating surface and transmit their heat to thin columns of air rising 50 through the hollow partitions. Placing the

vent pipe 12 low down on the end of the rectangular metal box causes the burnt gases to ascend and then descend, in other words, have a somewhat circulating movement.

55 I claim:—

1. In a heater of the character described, a rectangular container having a burner arranged along the lower front edge thereof, a flue in the rear wall and parallel partitions arranged longitudinally of the container and stopping short of the front and rear walls thereof to form flat chambers adjacent the said front and rear walls, alternate sets of adjacent partitions being joined at the front and rear ends and the other sets being joined at the top and bottom to cause flat columns of air to rise between similar flat columns of heated gases traveling from the front to the rear.

60 2. In a heater of the character described, a rectangular container having a burner arranged along the lower front edge thereof, a flue in the rear wall and parallel partitions arranged longitudinally of the container and stopping short of the front and rear walls thereof to form flat chambers adjacent the said front and rear walls, alternate sets of adjacent partitions being joined at the front and rear ends and the other sets being joined at the top and bottom to cause flat columns of air to rise between similar flat columns of heated gases traveling from the front to the rear with a hood on top of the container arranged to deflect the rising columns laterally 65 and to discharge the same downwardly.

70 3. In a heater of the character described, a rectangular container having a burner arranged along the lower front edge thereof, a flue in the rear wall and parallel partitions arranged longitudinally of the container and stopping short of the front and rear walls thereof to form flat chambers adjacent the said front and rear walls, alternate sets of adjacent partitions being joined at the front and rear ends and the other sets being joined at the top and bottom to cause flat columns of air to rise between similar flat columns of heated gases traveling from the front to the rear, the flue being arranged slightly higher 75 than the burner.

JOSEPH DAVID SCHMIDT.
